VICTOR G. GILBREATH AND SAMUEL T. WILLIAMSON, OF SEATTLE, WASHINGTON.

LUMBER BUNK.

Application filed February 27, 1924. Serial No. 695,458.

To all whom it may concern:

Be it known that we, VICTOR G. GILBREATH and SAMUEL T. WILLIAMSON, citizens of the United States, residing at 5 Seattle, in the county of King and State of Washington, have invented a certain new and useful Lumber Bunk, of which the following is a specification.

Our invention relates to an improvement 10 in lumber bunks for dry kiln trucks. More particularly, our invention relates to a lumber bunk designed to take up the slack which develops in the load of lumber by reason of the drying operation, thereby providing the 15 lumber being treated at all times with firm support, so that warping and distortion of the said lumber is prevented.

In drying lumber in kilns, the lumber 20 is frequently stacked on bunks in vertically disposed layers between side stakes. The lumber may be held between said stakes fairly tightly when loaded, but as the lumber dries, it shrinks, thereby creating slackness 25 between the layers, which permits distortion of the lumber. The shrinkage in the width of a load varies from two to five inches. It will be noted that the forming 30 of this two to five inches of slackness is done gradually during the operation of drying over a considerable period of time.

Devices in operation as heretofore designed have provided spring means to take up such slackness as develops during the drying operation. A serious objection obtains 35 as to such mechanism in that the amount of tension that is maintained on the lumber is not of such magnitude as to effectively accomplish the ends indicated. This is due to a further condition which must be 40 met by any practically operative device, which further condition is as follows: No matter how carefully the operators may be in piling the lumber, there is considerable slackness in the stack of lumber when the 45 load is made ready to enter the kiln. It will be understood that the lumber may be rough, i. e., unplaned, at the time of the dry kiln treatment. This means that there 50 are little projecting particles of wood or adhering sawdust or little splinters, which all tend to create a separation or spaced relation as respects the layers, hereinafter referred to as the initial slackness. A pri-

mary object of our invention is to provide a bunk which will take up this initial slackness previous to any operation of the means provided to take up the slackness during the drying operation which is subsequent in time.

The main difficulty in eliminating slackness in the load occurs at the bottom of the pile, i. e., on the bunk. The friction of the boards on the bunk, which is of great magnitude, due to the fact that the weight of the superposed layers is entirely carried thereby, makes it necessary for the application of considerable force to move the lumber together tightly before being placed in the kiln. A primary object of our invention is to provide a bunk having means which will supply the necessary magnitude of force to fully accomplish this end. At the top of the pile a well known and long used spring means is employed to hold the upper layers tightly together. No special 75 means for taking up the slackness is necessary due to the fact that there is not the high degree of pressure involved.

In providing a means which will take up the slackness during the drying operation, and also in providing a means to eliminate the initial slackness, there arises a condition which involves the necessity of means to put the spring under tension to permit of the loading of the bunk with lumber while the stake pocket is held in its most extended position, and then arises the necessity of locking the said spring in said extended position. Then upon releasing or tripping the spring, after the initial slackness is eliminated, it is necessary that the tripping means be thrown completely and positively out of action.

In providing such a lumber bunk means, a further important condition, which introduces difficulties, is that the "take up" or "throw" of the means must be as great as possible, and at the same time not strike or interfere with the lumber stacked on the bunk when loaded. It is a primary object 100 of our invention to provide a bolster which will meet and satisfy the requirements of proper degree of take up, as well as to provide a take up means which may be operable from the end of the loaded bolster.

A further primary object of our inven-

tion is to simplify the "throwing" or stretching of the spring and its release by providing for the same degree of "throw" by turning the wrench through an angle of ninety degrees (90°), that is now secured by turning it through one hundred and eighty degrees (180°).

The above mentioned general objects of our invention, together with others inherent in the same, are attained by the device illustrated in the following drawings, the same being merely a preferred exemplary form of embodiment of our invention, throughout which drawings like reference numerals indicate like parts:

Figure 1 is a view in side elevation of a lumber bunk embodying our invention, with a portion of the load shown mounted thereon;

Fig. 2 is an enlarged top view of said lumber bunk;

Fig. 3 is a view on dotted line 3, 3 of Fig. 2;

Fig. 4 is an end view in elevation of one end of said bunk on line 4, 4 of Fig. 2;

Fig. 5 is an enlarged top view of the initial take up end portion of said lumber bunk;

Fig. 6 is a view in perspective of the nut means constituting a part of said invention;

Fig. 7 is a view in perspective of the crank means of our invention;

Fig. 8 is a view in side elevation of the stake pocket and the end of the bunk oppositely disposed to the end which is provided with the initial take up means;

Fig. 9 is a view of the link means attached to the nut and lying along each side of the stake pocket on the end having the initial take up means;

Fig. 10 is a view of the link means connecting the crank means to the shaft of the nut link means;

Fig. 11 is a view in perspective of the link means connecting the spring with the shaft of the nut link means; and

Fig. 12 is a view of the U-shaped coupler used at each end of the bunk.

A bunk bolster 13 is preferably formed of two channels 14 and 15, preferably secured together at the end portions by two U-shaped coupler members 16 and 17, and also by separator members 18. Stake pockets 19 and 20 are slidably disposed in said end portions of the bunk bolster.

We will now describe the initial take up end portion of the lumber bunk bolster embodying our invention, and then follow with a description of the opposite end. Nut link means 21 and 22 (Fig. 9) are disposed on each side of stake pocket 19, passing through grooves 23 and 24 of said stake pocket 19. In one end of said link means 21 and 22, a nut 25 is mounted. Said nut 25 is provided with a threaded opening 26 in which is op-

eratively disposed a takeup screw 27, one end of which is disposed to bear against the stake pocket 19, so that said stake pocket may be forcibly moved towards the center of said lumber bunk bolster, being slidably disposed both as respects the channel members 14 and 15, and also with respect to the nut link means 21 and 22. In the other end of said nut link means, a shaft 28 is disposed. Near the inner end of the coupler member 16, a crank means 29 is disposed, mounted as respects its end portions in channels 14 and 15. This crank means 29 is connected to the shaft 28 by means of the crank link means 30, which is rotatably mounted both as respects said crank and said shaft. The shaft end of said crank link means 29 is preferably provided with a slot 31 to permit of the proper operation of the crank, and more particularly to provide for the positive locking, when desired, of the crank into inoperative position by permitting the crank to drop below.

Intermediate the ends of the bunk bolster embodying our invention, we provide a spring 32. Spring link means 33 connects one end of said spring 32 to the shaft 28. Stop 34 limits the rotation upwardly of the crank 29.

As respects the end of the lumber bunk bolster oppositely disposed to the initial take up end: The stake pocket 20 is provided on its inner side with a lug 35 (see Figs. 8, 2 and 3). In this lug 35, a shaft 36 is provided. Near the inner end portion of the coupler member 17, a crank means 37 is rotatably mounted as respects its end portions in the channel members 14 and 15. A crank link 38 connects the crank 37 to the shaft 36. This crank link means is provided with a forked end having slots 39, which engage shaft 36. The spring 32 is provided as respects one end portion with a link means 40, the ends of which engage shaft 36. Stop 41 limits the rotation upwardly of crank means 37.

The mode of operation of a lumber bunk embodying our invention is as follows: It will be understood that at different points of the load, lumber bunk bolsters embodying our invention are disposed. Before any loading of the bunk is commenced, a long handled wrench (not shown) is applied to the crank means 29 and 37, and the same are forcibly rotated clockwise into position shown in Figs. 2, 3 and 5, i. e., until they strike against stops 34 and 41. This extends the spring 32 and renders the same ready to apply its force to the lumber when the means holding it in said extended position is moved into releasing position. The screw 27 is also turned, so that the stake pocket 19 may be moved to its outermost position as shown in Figs. 2 and 3. It will be noted that the spring link means 33 and 40 extend

upwardly for a part of their length, so that when the crank means 29 and 37 are forced into position to stretch the spring 32, the link means may rest on top of the crank means. The crank means is disposed to move past, i. e., above, the line joining the center 42 of shaft 28 and the rotation center 43 of the crank means 29, so that the spring 32 is locked in extended position during the period of loading. The same principle applies to crank 37.

As respects the stake pocket at the end of the bunk bolster opposite to the take up means, the same general mode of operation obtains only there is no initial take up means as supplied by means of the screw 27 and nut 25 and associated parts.

With the stake pockets located in their outermost positions, stakes 44 are disposed in said pockets and the lumber is stacked therebetween, with spacer members 45 disposed between the tiers of lumber. When the load is complete, a wrench (not shown) is applied to the screw 27 and the stake pocket 19 is forcibly actuated towards the center of the bunk bolster without in any wise affecting the spring. This forcing of the stake pocket 19 inwardly takes up the initial slackness between the tiers of lumber.

This initial slackness is removed as respects each and every bunk bolster throughout the length of the load. Thereupon the wrench is applied to the crank means 29 and 37, and the same is rotated in a counter-clockwise position, so that the center of the crank means is turned towards the spring 32. This permits the tension of the spring to be applied through the spring link means 33, the shaft 28, to the nut link means 21 and 22, to the nut 25, through the screw 27, to the stake pocket 19, and thence to the lumber. It will be understood that screw 27 is freely mounted in separator 18. When the crank is thrown downwardly as just described, it is manifest that the slot 31 in the crank link means 30 insures the removal of all interference by the crank and its link means with the application of force from the spring 32 to the stake pocket 19, so that said crank is thrown positively out of action. The crank means 37 is thrown downward, so that the spring means 32 may apply its force to stake pocket 20 and thus the force of the spring is permitted to take up slackness by drawing in both stake pockets during the drying operation. Obviously, spring means 32 could be anchored as respects one end to the channel, and the take up means omitted as respects stake pocket 20. Such omission would be merely a cutting-down of the efficiency of the means provided.

Obviously, changes may be made in the form, dimensions and arrangement of the parts of our invention, without departing

from the principle thereof, the above setting forth only a preferred form of embodiment.

We claim:

1. A lumber bunk embodying a bunk bolster; a stake pocket slidably mounted upon one end of said bolster; a screw means operatively disposed with respect to said stake pocket, whereby said pocket may be actuated longitudinally of said bolster; a crank operatively mounted in said bolster; a spring; a link means connecting said spring and said screw means; and another link means connecting said crank to said screw means.

2. A lumber bunk embodying a bunk bolster: a stake pocket slidably mounted upon one end of said bolster; a link means slidably disposed in the side walls of said stake pocket; a nut carried by one end of said link means; a shaft connecting the opposite end of said link means; a crank operatively mounted in said bolster; a spring; a second link means connecting said spring and said shaft to said first named link means; a third link means connecting said shaft to said crank; and a screw operatively disposed in said nut, whereby it may be caused to bear against said stake pocket.

3. A lumber bunk embodying a bunk bolster; a stake pocket slidably mounted upon one end of said bolster; a link means slidably disposed in the side walls of said stake pocket; a nut carried by one end of said link means; a shaft connecting the opposite end of said link means; a crank operatively mounted in said bolster; a spring; a second link means connecting said spring and said shaft in said first named link means; a third link means connecting said shaft to said crank; a screw operatively disposed in said nut, whereby it may be caused to bear against said stake pocket; a second stake pocket slidably mounted upon the other end of said bolster, having a shaft supporting lug; a shaft in said lug; a second crank operatively mounted in said bolster; a fourth link means connecting said spring to said second crank; and a fifth link means connecting said second crank to said last named shaft.

4. A lumber bunk embodying a bunk bolster; a stake pocket slidably mounted upon one end of said bolster; a link means slidably disposed in the side walls of said stake pocket; a nut carried by one end of said link means; a shaft connecting the opposite end of said link means; a crank operatively mounted in said bolster; a spring; a second link means connecting said spring and said shaft in said first named link means; a third link means connecting said shaft to said crank, said link means having an oblong slot in which said shaft may lie, thereby providing a positive locking and tripping means for

said spring; a screw operatively disposed in said nut, whereby it may be caused to bear against said stake pocket; a second stake pocket slidably mounted upon the other end of said bolster, having a shaft supporting lug; a shaft in said lug; a second crank operatively mounted in said bolster; a fourth link means connecting said spring to said second crank; and a fifth link means connecting said second crank to said last named shaft.

5. In combination with a lumber bunk

bolster, a stake pocket slidably mounted upon one end of said bolster, a spring, means connecting said spring to said pocket, 15 and an initial take up means, whereby said stake pocket may be actuated longitudinally of said bolster without lessening the tension in said spring.

In witness whereof, we hereunto subscribe our names this 16th day of February, A. D. 1924.

VICTOR G. GILBREATH.
SAMUEL T. WILLIAMSON.
